UNITED STATES PATENT OFFICE

CARL H LARSON, OF ELKHART, INDIANA, ASSIGNOR TO THE ADLAKE COMPANY, A CORPORATION OF ILLINOIS

ELECTRIC HAND LANTERN

Application filed October 27, 1930. Serial No. 491,503.

This invention relates to improvements in electric hand lanterns, and has for its objects to produce a lantern having a strong weather-tight casing, a minimum number of parts, a dust and grit tight enclosure, and having a simplicity of construction and a surety of operation which will adapt the lantern to the rigid standards of railway signal equipment.

10 These and other objects and advantages of the invention will appear from the following description taken in connection with the accompanying drawing in which

Fig. 1 is an elevation of the lantern;

15 Fig. 2 is a sectional elevation of a portion of the lantern as indicated by the lines 2—2 of Fig. 1;

20 Fig. 3 is a plan view of the lantern looking into the interior of the casing, from which the battery has been removed, as indicated by the lines 3—3 of Fig. 4;

25 Fig. 4 is a vertical elevation of a portion of the lantern at right angles to the view shown in Fig. 2, as illustrated by the line 4—4 of Fig. 2;

Fig. 5 is a top plan view of the portion of the lantern below the line 5—5 of Fig. 4; and

30 Fig. 6 is a bottom plan view of that portion of the lantern above the line 6—6 of Fig. 4.

The lantern, generally indicated by the reference numeral 10, is composed of a casing 11, a base 12, a removable cover 13 and a looped handle 14. The handle is attached 35 to the casing by means of the trunnions 15 and 16. The base, as is illustrated, comprises a bottom ring 17, preferably having a larger diameter than the casing 11 in order to afford better protection for the lamps. Legs 18, 18 engage the base ring and support an upper casing engaging ring 19.

35 In Fig. 2, it will be seen that the casing 11 preferably is formed to have an integral bottom 21. The casing may, if desired, have a locating bead 22 rolled around its circumference.

40 Electrical connections with the battery 23 are formed by the engagement of its spring contact 24 with the bottom 21 and the engagement of its central spring contact 25

with a contact stud 26 which projects through the closed end of the casing and is insulated therefrom. The insulating means comprises a disk 27 of some acceptable insulating material, and a spacing washer 28 which prevents contact between the shank 29 of the stud 26 and the bottom 21. Two disks of insulating material, 31 and 32, are maintained against the outer surface of the bottom 21 by the rivetting over of the shank 30 and by the rivet 33. The outer of the two disks bears a laterally extending contact strip 34 which is electrically connected to the stud 26. The strip may be held upon the outer disk 32 by means of the countersunk rivets 35, 35. The upper disk 31 prevents the heads of these rivets from contacting with the bottom 21 of the casing.

45 In Figs. 2 and 4, it will be seen that the engaging ring 19 of the base is turned inwardly at 36 to form a circumferential lip and that this lip engages a flange 37 of a socket support 38. Preferably this element performs the function of a reflector in which case, it is desirable that it be circular as shown and that its outer surface be plated and polished. The support 28 is free to oscillate through a limited arc and may be turned by the handles 39, 39.

50 As indicated on Fig. 5, a small segment 41 of the flange 37 is cut away leaving two shoulders 42, 43 which hit against the stop pin 44. Lamp sockets 45 are attached to the support 38 by any suitable means and are here shown as soldered to it. The sockets comprise a metal shell 46 over which is fitted a spacing collar 47. The lower portion 48 of the shell is threaded to receive a lamp base while the upper portion 49 is counterbored. A small insulating washer 51 is seated upon 55 the shoulder formed between the counterbore and threaded portion, and an inverted insulating cup 52 lines the counterbore. A spring 53 is urged into the cup 52 and a plunger 54 having a lateral flange seated on the washer 51 is urged outwardly in the opposite direction by means of the spring 55 to engage the central terminal of the lamp base.

55 Depressions 56 are formed in the contact 100

strip 34 and other depressions 57, 57 are formed in the insulating disk 29. Plungers 53, 53 engage these depressions alternatively and, consequently, lock the switch in its on or off position.

- The screws 58 may hold the legs 18 onto the engaging ring 19 as well as anchor the casing to the ring 19 or the legs may be permanently attached to the ring and a clearance hole through the thickness of the ring and leg be provided for the screw. In either case, it is preferable to reinforce the casing with some extra thickness of metal at the points 59, 59 to provide sufficient engagement for the screw threads.

As the handles 39 are pushed horizontally, the support 38 turns and brings either one or the other of the spring pressed plungers 53 into engagement with the contact strip 34, which causes its respective lamp 61 to light. In the other position, both of the plungers 53 engage the depressions 57.

The demands of railway practice, for which this lamp was designed, require that a lamp be always held in readiness in case of a failure of the bulb being used. The mechanism here shown makes it possible to switch instantly from one lamp to the other. It is, however, to be understood that the presence of two lamps is not the essence of the invention, but that the switch mechanism is equally adaptable whether one or a multiplicity of lamps be required.

It is thus to be seen that I have produced a very rugged, dirt and dust tight lantern which has extreme mechanical simplicity and has no slot or opening into the battery casing or switch mechanism through which dirt and cinders might be forced to interfere with the operation of the device.

What I claim, therefore, is:

1. In an electric lantern, a casing for a battery having a central insulated battery contact and a lateral grounded contact, a battery, a base, a support having a portion engaged by the base and having turning movement relative thereto when the parts are assembled, a lamp socket carried by the support having its shell in electrical connection with the casing, a central contact on the socket, a contact strip upon the casing in electrical connection with the central battery terminal therein, and means causing the contact strip and the central socket contact to engage upon the relative rotative movement of the support and the casing.

2. In an electric lantern, a battery casing, a base having an upper portion engaging the casing, a reflector rotatably maintained within the upper portion of the base, an electric socket depending from the reflector and provided with two contact elements, one of its contact elements being electrically connected thereto, an insulated contact strip maintained upon the casing, a battery having one

terminal electrically connected to the strip and the second to the casing, and means to rotate the reflector, whereby the second contact element of said socket may be engaged with and disengaged from said contact strip. 70

3. An electric lantern having a base, a casing having a permanently closed end telescoping into the base from above and adapted to receive a battery, an insulated contact upon the casing end and adapted to engage the central terminal of the battery, means for engaging the lateral terminal of the battery with the casing, a reflector bearing a lamp socket, and oscillatably maintained between the base and the casing, and an insulated contact strip upon the outer face of the end of the casing and in electrical communication with the central terminal and adapted to engage the central terminal of the lamp socket upon the turning of the reflector. 80

4. In an electric lantern in combination, a casing for a battery and having a carrying bail and a depending guard frame and support, a battery within the casing and having one pole connected therewith, an oscillatable metal plate below the casing and supported thereby and being in electrical communication therewith, a depending lamp socket carried by the plate and electrically connected therewith and being located away from the center thereof, a spring contact element projecting upwardly from the socket, and a fixed conductor arranged for connection with the other pole of the battery and projecting into the path of the named socket contact element. 100

5. In an electric lantern, the combination of a battery casing of conductive material having a permanently closed bottom, said casing being in electrical connection with one terminal of the battery, an insulated contact on the inner surface of the casing bottom electrically connected to the other terminal of the battery, a lamp having one terminal electrically connected with the casing and movable relative to the casing to bring the other terminal into electrical connection with the insulated contact, and a skeleton base for supporting the casing in an upright position. 105

6. In an electrical lantern, the combination of a battery casing having a permanently closed bottom, a battery having one terminal in contact with the casing, a contact for engaging the other terminal of the battery mounted on the inner surface of the casing bottom but insulated therefrom, a reflector bearing a lamp rotatably mounted beneath the casing, a skeleton base mounted on the casing to support the latter in an upright position, and means causing a circuit to be established through the lamp by rotation of the reflector. 115

7. In an electric lantern, the combination of a metallic battery casing having a permanently closed bottom, a central contact member fixed to but insulated from the inside of 120

the casing bottom and adapted to engage the central terminal of the battery, the other terminal of the battery being adapted to contact with the casing, an insulated contact strip upon the outer face of the casing bottom in electrical connection with the central contact member, a lamp support including a lamp socket rotatably mounted below the casing, said lamp socket being in electrical communication with the casing through the lamp support, a lamp in the socket, and means for completing a circuit through the lamp by rotation of the lamp support.

8. In an electric lantern, the combination of a cup-shaped metallic casing adapted to removably contain a battery, an insulated contact permanently fixed to the inner face of the casing bottom and adapted to engage one terminal of the battery, the other terminal of the battery being in electrical communication with the metallic casing, an insulated contact strip permanently fixed to the under side of the casing bottom, means for rotatably mounting a lamp on the under side of the casing having one terminal in constant electrical communication with the casing, said lamp being so arranged with respect to the insulated contact strip on the outer face of the casing bottom that the other terminal of the lamp may be brought in and out of electrical connection with the contact strip by rotation of said mounting means.

In testimony whereof I affix my signature.

CARL H. LARSON.
